United States Patent Office.

ASA SNYDER AND ALEXANDER DELANEY, OF RICHMOND, VIRGINIA.

Design No. 3,043, dated May 12, 1868.

DESIGN FOR A BOX-STOVE.

The Schedule referred to in these Letters Patent and making part of the same.

TO ALL WHOM IT MAY CONCERN:

Be it known that we, ASA SNYDER and ALEXANDER DELANEY, of Richmond, in the county of Henrico, and State of Virginia, have designed a Box-Stove, of which the following is a full, clear, and exact description, reference being had to the accompanying drawing, making part of this specification.

Our invention is illustrated by a perspective view.

The body of the stove bulges out along the sides, from the top and bottom to the middle, and at the front end, both from top and bottom to the middle, and from the vertical edges to the middle also. The sides are vertically corrugated, as is the door at the front end; and in a scroll above the door is placed the motto or name of the stove, "Dixie." The top plate, bottom plate, and hearth, at the front end, are moulded substantially as shown in the drawing.

Having thus described my invention, what I claim as new, and desire to secure by Letters Patent, is—
The design for a box-stove, substantially as herein described and shown.
